UNITED STATES PATENT OFFICE

151,074

DESIGN FOR A HEAT INSULATED STORAGE RECEPTACLE

Louis M. Schnitzer, Brooklyn, N. Y., assignor to
Everlast Metal Products Corp., a corporation
of New York

Application January 20, 1947, Serial No. 136,254

Term of patent 14 years

(Cl. D44—8)

To all whom it may concern:

Be it known that I, Louis M. Schnitzer, a citizen of the United States, residing at Brooklyn, in the county of Kings, State of New York, have invented a new, original, and ornamental Design for a Heat Insulated Storage Receptacle, of which the following is a specification, reference being had to the accompanying drawing, forming part thereof.

The figure is a front elevational view of a heat insulated storage receptacle, showing my new design. The receptacle is substantially circular in section throughout its height. A rear elevational view would substantially correspond to the view depicted.

I claim:

The ornamental design for a heat insulated storage receptacle, as shown and described.

LOUIS M. SCHNITZER.
